UNITED STATES PATENT OFFICE.

FRED F. SEMM, OF CHARLES CITY, IOWA.

PUMP ATTACHMENT.

SPECIFICATION forming part of Letters Patent No. 712,010, dated October 28, 1902.

Application filed May 25, 1901. Serial No. 61,921. (No model.)

To all whom it may concern:

Be it known that I, FRED F. SEMM, a citizen of the United States, residing at Charles City, in the county of Floyd and State of Iowa, 5 have invented a new and useful Pump Attachment, of which the following is a specification.

This invention is an improved pump-operating device adapted for use in connection 10 with pumps operated by means of a windmill.

The object of this invention is to provide an attachment by means of which the pitman of the windmill can be quickly and easily 15 thrown into or out of engagement with the piston-rod of the pump.

Another object of the invention is to provide an attachment in which the ordinary hand-lever can be operated for the purpose 20 of working the pump-piston, said hand-lever also serving to throw the pump-piston into engagement with the windmill-pitman whenever desired.

With these objects in view my invention 25 consists in the peculiar construction of the various parts and in their novel combination and arrangement, all of which will be fully described hereinafter and pointed out in the claims.

30 In the drawings forming a part of this specification, Figure 1 is a side elevation of the pump attachment constructed in accordance with my invention. Fig. 2 is a vertical sectional view. Fig. 3 is a detail perspective 35 view of the plate for disengaging the pump handle or lever from the piston-rod. Fig. 4 is a detail view showing the engagement between the coupling-bar and piston-rod. Fig. 5 is a section on the line 5 5 of Fig. 1. Fig. 40 6 is a detail perspective view of the buckle for connecting the spring to the piston-rod. Fig. 7 is a detail perspective view of the dog for locking the handle-lever to the piston-rod, and Fig. 8 is a detail perspective view of the 45 pin secured to the spring-pawl carried by the coupling-bar.

In carrying out my invention I employ a coupling-bar A, which is adapted to be secured to the end of the windmill-pitman, said 50 coupling-bar having one or more serrated openings A', produced near the upper end, to receive the square shank of the coupling-

bolt, the serrations permitting the necessary adjustment being superior to having a series of bolt-openings. The coupling-bar A has a 55 vertical socket A², produced in its lower end and in which works the upper end of the piston or sucker rod B of the pump, said piston-rod working through the pump-head C. A spring bail or pawl D is pivoted to the coupling-bar A adjacent to its lower end and is adapted to swing beneath the said bar, and a spring E is fastened to the bar and presses upon the free end of the bail or pawl D for the purpose of throwing it beneath the end 60 of the bar A. This bail or pawl D is intended to engage a notch B', produced in the edge of the piston-rod B, thereby completing the engagement or coupling between the bar A and the piston-rod B, and as the coupling-bar is 65 reciprocated in unison with the windmill-pitman the piston-rod of the pump will of course be reciprocated also. In case the bail or pawl D should fail to spring into the notch B' it will be sure to engage the notch B², inasmuch 70 as the said notch has a beveled face, and when the bail or pawl engages the notch B² it will force the piston-rod down and upon the return stroke the said bail or pawl will 75 surely engage the notch B'. 80

The pump-head C has two upright standards C' attached thereto, the upper ends of said standards being bent horizontally, as shown at C², guide-rollers C³ being pivoted between the arms C² for the purpose of guiding the piston-rod B. A fulcrum-arm F is pivoted to the pump-head C, and the operating handle or lever G is pivoted to the said fulcrum-arm F, the end of said handle or lever being pivotally connected to a box H, 85 formed of two sections and sliding upon the piston-rod B, said box being moved up and down by means of the handle or lever G. A dog H' is pivoted within the box H, and a spring H² normally presses the free end of 90 said box against the face of the rod B, and a notch B³ is produced in the face of said rod, so that when the handle or lever is raised and the box moved down to the position shown in dotted lines in Fig. 1 the dog H' will be 95 sprung into engagement with the notch B³, thereby coupling or connecting the piston-rod to the handle or lever, and by reciprocating the said handle or lever the piston-rod

will be reciprocated and the pump worked. The dog H⁷ has a finger H⁸, which extends through a curved slot H⁴ produced in the side of the box.

- 5 I indicates a plate attached to the outer side of one of the arms C², said plate extending downwardly and having a cam-face I', which is adapted to engage the finger H⁸ and throw the dog out of the notch B³ whenever 10 the handle or lever is thrown down to its full extent, thereby causing the box H to be moved up to such a height that the edge of the plate I will engage the pin or finger H⁸. It will thus be seen that the handle or lever 15 can be quickly and easily coupled or connected to the piston-rod for the purpose of reciprocating the same and that by forcing the end of the lever downwardly to its full limit the box will be forced upwardly to its full 20 limit, disengaging the spring-dog from the piston-rod.

In order to throw the coupling-bar out of engagement with the piston-rod when the handle or lever is thrown into engagement 25 and also to throw the coupling-bar automatically into engagement as soon as the handle or lever is disengaged, I employ a lever K, which is pivoted to the plate I and works through an eye K', swiveled upon the corner 30 of the box H. The upper end of this lever K is connected to a bar L, said bar L being connected at its upper end to a link M, which in turn is pivotally connected to the upper end of the bar N, which extends upwardly 35 from the arm C² through an eye N', arranged upon the side of the coupling-bar. The bar L is curved outwardly, as shown at L', so as to make connection with the end of the lever K.

- 40 When the box H is moved upwardly to disengage the handle or lever from the piston-rod, the lever K is turned upon its pivot through the medium of the eye K', and the bar L is thrown inwardly, releasing the pawl 45 or bail, said arm having previously engaged the pin L², secured upon the side of the bail or pawl for the purpose of holding same out of engagement with the notches B' and B². The moment, however, the box is elevated 50 and the bar L thrown back into the position shown in Fig. 1 the spring E will force the bail or pawl into engagement with the notches B' or B², thus effecting the engagement or coupling of the bar A with the rod B. In 55 this manner the wind-power is immediately brought into engagement with the pump-rod the moment the hand-power is released, and it should be stated here that by arranging the pin L² eccentrically upon a head L³ and connecting the latter to the bail D the pin may 60 be adjusted to take up any wear of the bar L that may be caused by the bar and pin engaging each other, and, further, by corrugating the face of the head the danger of it slipping 65 after adjustment is positively avoided.

H⁵ indicates a guide-lug which rests behind the straight shoulder I² of the plate I

when the wind-power is in operation, thereby preventing the box H causing any friction upon the pump-rod.

70

In order to take up the shock or jar incident to the dropping of the piston-rod from the coupling-bar and incidentally to support the weight of the piston-rod, I employ a bow-shaped spring O, the lower end of which is 75 adapted to rest upon the pump-head C, while the upper end is connected to the piston-rod by means of a buckle P, which is pivotally connected to the said piston-rod. This buckle is bifurcated, as shown at P', for the 80 purpose of straddling the piston-rod, and the bifurcations have recesses P² to receive the pin P³, which is passed through the coupling-rod. This buckle also has two cross-bars P⁴ and P⁵ adjacent to the opposite end, and the 85 end of the spring O is of peculiar formation in order to fit into the buckle and engage the cross-bars, said spring being curved upwardly, as shown at O', to pass over the bar P⁴ and downwardly, as shown at O², to pass 90 under the bar P⁵, thereby securely fastening the end of the spring to the buckle. As before stated, this spring will help to support the piston-rod and will take up the jar when the piston-rod is disengaged from the coupling-bar, for the reason that as the piston-rod is lowered the spring is bent and the increase of tension caused thereby will be sufficient to entirely support the said piston-rod and will therefore take up the said jar, as before 95 stated.

It will thus be seen that I provide a simple and efficient attachment for automatically connecting and disengaging hand and wind power to the piston-rod of the pump. 105 The upper end of the operating handle or lever G is bifurcated in order to straddle the sliding box H, said bifurcated end being secured to the said box by means of bolts H⁶, which are threaded at their inner ends to engage screw-threaded holes in the sides of the box; but the said bolts are smooth where they pass through the members of the handle, so that said handle can turn freely on the said bolts. It will also be noted that the lever or 110 handle is bowed, so that an additional amount of leverage can be added for the purpose of projecting the box up into contact with the cam edge I. It will also be noted by referring to Fig. 5 that the rollers C³ are journaled 115 upon sleeves C⁴, so that the bolt can be securely clamped between the arms C² without danger of binding upon the rollers, and it will also be noted that the said arms are slotted longitudinally adjacent to their outer 120 ends, so that the outer roller can be easily adjusted.

Having thus fully described my invention, what I claim as new, and desire to secure by Letters Patent, is—

130

1. The combination with the coupling-bar, piston-rod and operating handle or lever, of the spring-actuated bail or pawl carried by the coupling-bar and adapted to engage the

piston-rod, a box sliding upon the piston-rod and pivotally connected to the operating handle or lever and having a pawl or dog adapted to engage the piston-rod, a stationary plate 5 arranged to disengage the said pawl or dog, and means attached to said plate for disengaging the pawl or bail arranged upon the coupling-bar, substantially as described.

2. In a pump, the combination with the 10 coupling-bar, piston-rod, operating-handle and guide-standards, of the spring-actuated bail or pawl carried by the coupling-bar and adapted to engage the piston-rod, a box sliding upon the piston-rod pivotally connected 15 to the operating handle or lever and having a spring-actuated pawl or dog adapted to engage the piston-rod, a plate supported by the guide-standards and adapted to disengage the said pawl or dog, a lever pivoted to the said 20 plate and operatively connected to the sliding box, and also a rod or bar for disengaging the bail or pawl carried by the coupling-bar, substantially as shown and described.

3. In a pump attachment, the combination 25 with the coupling-bar, piston-rod, operating-handle and guide-standards, of the box sliding upon the piston-rod and carrying a spring-actuated pawl, the plate for disengaging said pawl, the lever pivoted to the plate and working 30 through an eye carried by the box, the bar pivotally connected to the upper end of said lever, the pawl or bail attached to the coupling-bar and having a pin adapted for engagement with the said bar, upright rod 35 attached to the guide-standard and pivotally

connected to the disengaging-bar, substantially as set forth.

4. In a pump attachment, the combination with the coupling-bar having a spring-actuated bail or pawl, of the piston-rod having 40 notches, of the operating handle or lever, the pump-head having guide-standards, the guide-rollers attached to the said standards, the plate supported by the standards, the sliding box having a spring-actuated pawl carrying 45 a pin projecting through the side of the box and adapted for engagement with the plate, the lever pivoted to the plate and working through an eye carried by the box, the disengaging-bar pivoted to the lever, the upright 50 rod extending from the guide-standard, and the link connection between said rod and disengaging-bar and the pin upon the side of the bail or pawl, substantially as shown and described. 55

5. In a pump attachment, the combination with the piston-rod having the pin extending therethrough, a buckle comprising a bifurcated frame which is adapted to straddle the piston-rod and embrace the pin, said frame 60 having two cross-bars and the bow-spring having its upper end shaped to fit over the first cross-bar and under the second one, the lower end of said spring being adapted to rest upon the pump-head, substantially as set forth. 65
